UNITED STATES PATENT OFFICE.

GEORGE RICHARD MEISSNER, OF ALBIA, IOWA, ASSIGNOR OF ONE-HALF TO L. R. WEST,
OF OSCEOLA, IOWA.

SPARK-INTENSIFIER FOR SPARK-PLUGS.

1,190,570.

Specification of Letters Patent. Patented July 11, 1916.

Application filed October 16, 1914. Serial No. 866,969.

To all whom it may concern:

Be it known that I, GEORGE RICHARD MEISSNER, a citizen of the United States of America, residing at Albia, in the county of Monroe and State of Iowa, have invented 5 certain new and useful Improvements in Spark-Intensifiers for Spark-Plugs, of which the following is a specification, reference being had therein to the accompanying 10 drawing.

This invention relates to certain new and useful improvements in spark intensifiers for spark plugs, the object being to provide a spark intensifier which is exceedingly 15 simple and cheap in construction and one in which the spark gap is clearly visible from any angle in order that any defects in the ignition system of internal combustion engines can be readily detected.

20 Another object of my invention is to provide a spark intensifier in which a pair of screw electrodes are employed which can be adjusted in respect to each other in order to increase or decrease the spark gap; means 25 being provided on one of the electrodes for connecting one of the circuit wires; the other electrode having a flattened head to allow the same to be connected to one of the electrodes of the spark plug.

30 I am aware that spark intensifiers have been made in which a tube of insulating material formed a support for the electrodes; said tube having a transverse bore in order to enable the spark gap to be seen. 35 However, in installing this form of spark intensifier in connection with an ignition system in an automobile, it very often happens that the spark gap cannot be seen.

With my improved construction, a pair of 40 insulating disks are employed for supporting the electrodes and said disks are spaced and inclosed in a glass casing which allows the spark plug to be seen from any angle at the same time, a construction of spark intensifier is formed, which is exceedingly 45 strong and durable and which can be readily assembled and taken apart.

Other and further objects and advantages 50 of the invention will be hereinafter set forth and the novel features thereof defined by the appended claims.

In the drawings, Figure 1, is a perspective 55 of my improved construction of spark intensifier; and Fig. 2, is a longitudinal section through the same.

Like numerals of reference refer to like parts in the several figures of the drawings.

In carrying out my invention, I employ a pair of circular disks 1 and 2 preferably formed of good insulating material which are provided with oppositely disposed sockets in their opposing faces in which are mounted spacing plugs 4 secured in position therein by screws 3 passing through the disks into bores formed in the ends of the 60 plugs 4 so as to form a rigid connection whereby the disks will be held properly spaced in such a manner that all danger of sparks jumping to the spacing plugs, is prevented, and a construction is provided 65 which is exceedingly simple and cheap to manufacture.

Arranged over the outer faces of the disks 1 and 2 are mica sheets 5 held in position thereon by metal caps 6 and 7 having central openings registering with openings formed in the mica sheets and threaded bores 8 formed in the disks 1 and 2 in which are mounted screw electrodes 9 and 10 having reduced ends 11, and it will be seen by 70 this construction that these reduced ends or points can be adjusted in respect to each other in order to increase or decrease the spark gap.

The screw electrode 10 is provided with a 85 flattened head 12 adapted to be connected to the electrode of the spark plug; said head forming means for turning the screw within its threaded bore by adjusting the position of the same. The screw electrode 9 is provided with a slotted end 13 to receive a screw driver for rotating the electrode within its threaded bore for adjusting the same, and mounted upon the outer end of said electrode 9 is a clamp nut 14 and a thumb 90 nut 15 by means of which, one of the conducting wires of the ignition system can be connected thereto, the clamp nut 14 serving to clamp the cap 6 in position upon the disk, and it will be noticed that the head 12 of 95 the opposing electrode, answers the same purpose.

The insulating disks and electrodes are enclosed by a blue glass tube 16 arranged within the flanges of the caps 6 and 7 which are 105 insulated as clearly shown. It will be seen that by incasing the electrodes in a blue glass tube, the spark is made visible from any angle.

From the foregoing description, it will be 110

seen that I have provided a spark intensifier for spark plugs in which the electrodes are adjustably mounted in respect to each other in order to increase or decrease the spark gap; said electrodes being mounted within a glass tube in order to allow the spark gap to be readily seen from any angle.

I claim:

1. A spark intensifier, comprising a pair of insulating disks, plugs for spacing said disks, electrodes adjustably mounted within said disks, a glass tube inclosing said disks, and caps secured on said disks by said electrodes engaging the ends of said glass tube.
- 15 2. A spark plug intensifier, comprising a pair of insulating disks provided with centrally arranged threaded bores, said disks being provided with sockets, spacing plugs mounted in said sockets, screws extending through said disks into said plugs, caps arranged on said disks, a glass tube arranged between said caps, and electrodes mounted within said threaded bores of said disks for holding said caps in position upon said insulating disks.
- 20 3. A spark intensifier, comprising a pair of insulating disks, electrodes adjustably mounted within said disks, means for holding said disks spaced apart, caps surrounding said disks and held in position thereon by said electrodes, and a glass tube arranged between said caps surrounding said disks.
- 25 4. As a new article of manufacture, a spark intensifier comprising a pair of opposed insulating disks, spacing plugs connecting said disks, means for securing said plugs to said disks, mica sheets arranged upon said disks, caps arranged upon said mica sheets, a glass tube arranged between said caps, and electrodes adjustably mounted within said disks for securing said caps in position upon said disks.
- 30 5. A spark intensifier, comprising a pair of spaced insulating disks provided with

centrally threaded bores, apertured sheets 45 of mica arranged upon the outer faces of said disks, apertured caps mounted upon said sheets of mica, a glass tube arranged between said caps and surrounding said insulating disks, and threaded electrodes 50 mounted within the threaded bores of said insulating disks having means for clamping said caps in engagement with the ends of said tube.

6. A spark intensifier, comprising a pair 55 of insulating disks having electrodes adjustably mounted therein, spacing members disposed between said disks, caps carried by said disks and secured thereon by said electrodes and a glass tube arranged within said 60 caps surrounding said disks and electrodes.

7. A spark plug intensifier, comprising a pair of insulating disks, spacing plugs connecting said disks, caps provided with marginal flanges mounted upon said disks, a 65 glass tube arranged between said caps engaged by the flanges thereof, and electrodes mounted within said insulating disks having means for engaging said caps for clamping said tube between said caps.

8. A spark plug intensifier, comprising a pair of insulating disks provided with centrally arranged threaded bores and oppositely disposed sockets upon their opposite faces, plugs having their ends seated in said 75 sockets, screws passing through said disks into said plugs, caps provided with marginal flanges mounted upon said disks, a glass tube arranged between said caps and embracing said disks, and electrodes mounted within said insulating disks having means for engaging said caps.

In testimony whereof I hereunto affix my signature in the presence of two witnesses.

GEORGE RICHARD MEISSNER.
